UNITED STATES PATENT OFFICE.

WILLIAM E. BERTRAM, OF BROOKLYN, NEW YORK, ASSIGNOR TO INTERNATIONAL
TYPESETTING MACHINE COMPANY, OF NEW YORK, N. Y., A CORPORATION OF NEW
YORK.

LINOTYPE-MACHINE.

1,116,217.

Specification of Letters Patent.

Patented Nov. 3, 1914.

Application filed November 23, 1911. Serial No. 661,936.

To all whom it may concern:

Be it known that I, WILLIAM E. BERTRAM, a citizen of the United States, residing at Brooklyn, in the county of Kings and State of New York, have invented new and useful Improvements in Linotype-Machines, of which the following is a specification.

The present invention relates to improvements in linotype machines and more especially to the trimming knives whereby the slugs are trimmed to uniform thickness and irregularities and imperfections are removed, and the primary object of this invention is to provide improved means for mounting and adjusting the relation between the knives whereby they may be quickly and correctly set and locked in different relative positions to trim slugs to different standard thicknesses.

Another object of this invention is to provide simple and improved means whereby the angular relation between the knives may be readily adjusted in order to maintain the knives in parallelism and thus compensate for sharpening an uneven wear of the knives, and to provide a corresponding compensating adjustment for the knife-setting means.

To these and other ends, the invention consists in certain improvements and combinations and arrangements of parts, all as will be hereinafter more fully described, the novel features being pointed out particularly in the claims at the end of the specification.

In the accompanying drawing:—Figure 1 is a perspective view of the forward side of the vise and the knife block of a linotype machine embodying the present invention; Fig. 2 is a rear elevation of the parts shown in Fig. 1; Fig. 3 represents a horizontal section on the line 3—3 of Fig. 2 and looking in the direction of the arrows; Fig. 4 is a perspective view of the rear side of the swivel plate for the adjustable knife; and Fig. 5 is a perspective view of the adjustable knife.

Similar parts are designated by the same reference characters in the several views.

In linotype machines of the types commonly used, the cast slugs are ejected from the mold by an ejector blade which moves the slug edgewise, and this ejector blade forces the slugs between a pair of parallel knives which operate to trim the flat sides of

the slug and thereby remove irregularities and reducing the slugs to the proper standard thickness. In such machines, the molding apparatus enables slugs of different sizes to be cast and to enable the trimming mechanism to accommodate the slugs of different sizes, the knives are capable of relative adjustment to vary the distance between them to correspond with the thickness of the slugs of any selected size. The present invention provides improved means for mounting and adjusting one of the knives whereby the relative adjustment of the knives may be quickly set according to the different standard sizes of slugs which may be made in the machine, and simple means is also provided for relatively adjusting the knives in an angular direction in order to compensate for unevenness due to sharpening or wear. The means provided by the present invention for setting the knives for slugs of different standard sizes compensates for the relative angular adjustments between the knives.

The accompanying drawing shows the preferred embodiment of the invention, but it will be understood that the invention is not limited to the precise details and the relative arrangement of the parts, as modifications or changes may be made in the practical application of the improvements to different machines.

In the present instance, the knife block 1 is shown attached to the vise 2 of the machine, and one of the knives, the knife 3 in the present instance, is rigidly secured in fixed position on the vise 2 and at one side of the slot 4 through which the trimmed slugs discharge. The knife block at the opposite side of the slot 4 is formed with an extension 5 and a swivel plate or member 6 is applied to this extension, it being pivotally connected thereto by a screw or pivot 7 which is preferably arranged midway of the length of the knives. The pivotal connection between the swivel plate or member 6 and the knife block permits angular adjustments between these parts. To facilitate such adjustments, an adjusting screw 8 is provided, this screw being supported by an arm 9 which is attached to or forms part of the extension 5 of the knife block and the end of the screw bears against the adjacent side or edge of the plate or member 6, the screw operating in the

2
plane of this plate or member. In order to maintain the plate or member 6 in proper angular relation to the knife block, a screw or its equivalent 10 is employed, 5 this screw in the present instance passing through an aperture 11 in the plate or member 6 and also through a slot 12 in the arm 9, such slot being concentric with the screw 7 as an axis, and a nut 13 on the 10 screw 10 serves to clamp the plate or member 6 and the arm 9 firmly together, thereby preventing shifting of these parts after they have been set in proper angular relation.

The adjustable knife 14 is in the present 15 instance attached to a knife holder 15, and this adjustable knife and its holder are mounted and guided to move rectilinearly on the plate or member 6. In the present instance, the rear side of the knife 14 is 20 formed with a dove-tail rib 16 which operates longitudinally between complementary guides 17 on the adjacent face of the member 6. To insure rectilinear movement between the knife and its holder and the plate 25 or member 6, the holder is preferably formed at its rear end with a rib 18 which operates in a longitudinal groove 19 in the plate or member 6. Movement of the knife 14 and its holder relatively to the swivel 30 plate or member 6 serves to vary the distance between the knives to correspond to slugs of the size to be trimmed. In practice, the various sizes of slugs are known by points and the points vary in size by fourteen thousandths of an inch. The present invention 35 provides means whereby the relation or distance between the knives can be instantly set so as to operate properly upon slugs of any selected standard size and when so set, the knives are firmly locked in proper adjusted 40 relation. The means shown in the present instance for accomplishing these results embodies a graduated bar or member 20 which is provided with a series of apertures 21, 45 these apertures being spaced longitudinally of the bar or member and each of these apertures is located at a different distance from the operative edge of the adjustable knife 14. The difference in spacing of the 50 apertures 21 from the operative edge of the adjustable knife preferably corresponds to the difference between each point or standard type size in which case the difference in spacing between any two adjacent apertures 55 21 with respect to the operative edge of the adjustable knife will be fourteen thousandths of an inch. The member 6 is formed with a set of apertures 22 the longitudinal spacing of which agrees with the 60 longitudinal spacing of the apertures 21 in the graduated member 20, but the set of apertures 22 is parallel with the operative edge of the knife. Movement of the adjustable knife toward and from the stationary or 65 fixed knife will therefore cause the aper-

tures 21 in the graduated member 20 to successively register with the apertures 22, a different aperture 21 registering with a different aperture 22 for each movement of the adjustable knife to the extent of fourteen thousandths of an inch. The adjustable knife may be retained in the different adjusted positions by a locking pin 23 which is capable of insertion into one of the apertures 22 and the registering aperture 21 in 75 the graduated member. A scale 24, the indicating characters of which preferably correspond to the well known designations of the different points, is preferably provided for the set of apertures 22 in the member 6 80 whereby the locking pin 23 may be instantly inserted into the aperture 22 corresponding to the desired point, and when the adjustable knife has been moved into a position where the corresponding aperture 21 in the graduated member 20 registers with the aperture 22 containing the locking pin, this pin may be caused to enter the registering aperture 21 and the adjustable knife is then 85 properly set.

90 Adjusting movements of the knife 14 may be accomplished by different means, that shown in the present instance embodying a handle 25 which is mounted to rock on a pivot 26 supported at the forward side of the knife block extension 5, and the opposite end of this handle has a fork 27 which cooperates with a transverse pin 28, the latter being supported by lugs 29 on the knife holder 15. After the knife 14 has been 100 properly adjusted and set, it may be clamped firmly to prevent alteration of its adjustment. In the present instance, a screw 30 is provided the head of which bears on the knife holder 15 and the forward threaded end of this screw receives a clamping handle 31, the clamping handle bearing against the forward side of the swivel plate or member 6, the latter being formed with an elongated slot 32 to permit the passage 110 of the clamping screw 30 without interfering with the adjustment of the knife.

115 In order that the graduated bar or member 20 may be adjusted in accordance with angular adjustments of the swivel plate or member 6 to compensate for sharpening or uneven wear of the knives, this bar or member is made separately from the knife holder 15 and is seated in a transverse channel 33 which is formed in said knife holder, the 120 opposite walls 34 and 35 of said channel supporting screws 36 and 37, these screws being arranged in pairs and operating upon the respective longitudinal edges of the graduated bar. In order that these screws 125 may retain the graduated bar in proper position and prevent its displacement from the channel, the respective edges of the bar are beveled as at 38 and 39. Longitudinal movement of the graduated bar in the chan- 130

nel is prevented by a pair of shouldered screws 40 which extend through transverse slots 41 in the bar and are threaded into the apertures 42 in the bottom of the channel these screws, however, permitting the graduated bar to be adjusted in a direction toward and from the knives, the bar being held in different adjusted positions by the screws 36 and 37 which clamp the bar in operative position. The bottom of the channel 33 is provided with apertures sufficiently large to permit insertion of the pin 23 into the apertures 21 of the member 20 when the latter occupies different adjusted positions relatively to the channel.

In practice, the operative edges of the knives 3 and 14 are in parallelism and the graduated bar 20 is held in such position by the screws 36 and 37 that the registration 20 of each of the apertures 21 in this bar with the corresponding aperture 22 will occur when the knives are spaced apart a distance equal to the thickness of a slug of a corresponding size, and when the apertures corresponding to the selected size have been brought into register, the locking pin 23 may be readily inserted to retain the knives in set position, it being possible for the operator to readjust the knives for the different size slugs quickly and with the greatest facility. Should the parallelism between the operative edges of the knives be destroyed owing to sharpening, wear, or other causes, the knives are again brought into parallelism by shifting the swivel plate or member 6 about the screw 7 as a center until the edges of the knives are in parallel relation, this adjustment being effected by loosening the nut 13 and manipulating the screw 8, the swivel plate or member being again locked in its readjusting position by tightening of the nut 13. When it is necessary to readjust the angular position of the swivel plate or member 6 to restore the knives to parallel relation, the graduated bar or member 20 is correspondingly adjusted in its channel by manipulation of the screws 36 and 37 in order that the apertures 21 in this bar may occupy a proper graduated relation to the operative edges of the knives, and these screws 36 and 37 may also be adjusted to compensate for wearing away of the knives independently of the angular adjustment afforded by the swivel plate or member. These adjustments therefore enable the graduated setting means to maintain a proper relation to the knives at all times.

I claim as my invention:—

60 1. In a linotype machine, slug-trimming means embodying a fixed and a movable knife, in combination with a knife block, a support having the movable knife mounted thereon, a member secured to and movable with said support and provided with gradu-

ated knife setting devices, and means coöperative with said setting devices and support, to set and retain the knife in different adjusted positions relatively to said fixed knife.

70 2. In a linotype machine, slug-trimming mechanism embodying a fixed and a movable knife, in combination with a knife block, a support having the movable knife adjustably mounted thereon, a member movable with said support and having setting means spaced graduated distances in the direction of adjustment of the knife thereon, and means to coöperate with said setting means for correspondingly positioning the 80 movable knife.

3. In a machine of the class described, slug-trimming mechanism embodying, in combination, a knife block, a knife in fixed relation thereto, an adjustable knife, a member adjustably mounted on the knife block and having a row of setting apertures arranged at graduated distances from said adjustable knife mounted thereon, and means to coöperate with any one of said 90 apertures to retain the knife in a correspondingly adjusted position.

4. In a linotype machine, slug-trimming mechanism embodying, in combination, a fixed and a movable knife, a support having 95 the movable knife adjustably mounted thereon and provided with a transverse row of apertures located at graduated distances from the operative edge of said knife, the support having a row of apertures arranged 100 in parallelism with said knife edge, and a pin to enter the apertures of said row when in register to set the knife in different adjusted positions.

5. In a linotype machine, slug-trimming 105 mechanism embodying, in combination, a fixed and an adjustably mounted trimming knife, a graduated setting member movable with said adjustable knife, means coöperative with said member to set the adjustable 110 knife in different adjusted positions with respect to the fixed knife, and a compensating adjusting means between the knife and said member.

6. In a linotype machine, slug-trimming 115 mechanism embodying, in combination, a fixed and movable knife, a support having the movable knife adjustably mounted thereon and provided with a transverse channel, a member seated in said channel 120 and provided with a row of apertures spaced at graduated distances from said movable knife, a compensating adjusting means for varying the position of said member, and means coöperative with the graduated apertures of said member to retain the movable knife in correspondingly adjusted positions

125 7. In a linotype machine, slug-trimming mechanism embodying, in combination, a knife block supporting a knife, a swivel 130

member on the knife block, and a knife carrying support guided in its movement toward and from the knife first mentioned by said swivel member and capable of angular adjustment relatively to the knife first mentioned.

8. In a linotype machine, slug-trimming mechanism embodying a knife block having a knife thereon, a swivel member pivotally connected to the knife block, and a knife guided on said member to move toward and from the knife first mentioned and also adjustable with said member in angular relation to the knife first mentioned.

9. In a linotype machine, slug-trimming mechanism embodying, in combination, a knife block supporting a knife, a member swiveled on the knife block, an adjustable knife slideable on said member in a direction toward and from the knife first mentioned and also adjustable with said member in an angular direction, and knife setting means to connect said adjustable knife and the swiveled member.

10. In a linotype machine, slug-trimming mechanism embodying, in combination, a knife block supporting a knife, a member on said block adjustable angularly to said knife, an adjustable knife guided to move on

said member in a direction toward and from the knife first mentioned, knife setting means to connect said adjustable knife and member, and a compensating adjusting means for varying the angular position of the knife setting means.

11. In a machine of the class described, slug-trimming mechanism embodying, in combination, a pair of relatively movable trimming knives, a knife block having one of said knives arranged in fixed relation thereto, a support slidably mounted on the knife block and carrying the other knife, means for shifting the knife-carrying support into different operative positions relatively to said knife block, a member on said slideable support having knife-setting means spaced graduated distances from the knife thereon, and means adapted to coöperate with said setting means to position the knives in different operative relations.

In testimony whereof I have hereunto set my hand in presence of two subscribing witnesses.
